SELECTOR LEVER HANDLE FOR A
TRANSMISSION

Paul M. Malasky, Bloomfield Hills, Mich., assignor to
Chrysler Corporation, Highland Park, Mich., a corpora-
tion of Delaware

Filed May 22, 1969, Ser. No. 17,272

Term of patent 7 years

Int. Cl. D12—14; D8—03
U.S. Cl. D14—6FIG. 2. FIG. 1. FIG. 3. FIG. 4.

FIG. 1 is a side elevation of this invention;

FIG. 2 is a front view of FIG. 1;

FIG. 3 is a rear view of FIG. 1;

FIG. 4 is a side elevation similar to FIG. 1 taken from
the other side of this invention; and

FIG. 5 is a plan view of FIG. 4.

The gearshift lever, shown fragmentarily in broken
lines, is included for illustrative purposes only.

I claim:

The ornamental design for a selector lever handle for
a transmission, substantially as shown and described.
